Primary Examiner—Martie K. Holtje**[57] CLAIM**

The ornamental design for an ornamental design for a "refillable door knob tag note paper dispenser", as shown and described.

DESCRIPTION

FIG. 1 is a front elevation view of a refillable door knob tag note paper dispenser showing my new design;

FIG. 2 is a side elevation view, the other side being a mirror image thereof;

FIG. 3 is a bottom plan view thereof;

FIG. 4 is a top plan view thereof;

FIG. 5 is an enlarged fragmentary cross-sectional view of the perforation taken along lines 5—5 of FIG. 1;

FIG. 6 is a perspective view of FIG. 1 thereof;

FIG. 7 is a rear view thereof;

FIG. 8 is a perspective view of FIG. 7 thereof;

FIG. 9 is an exploded perspective view of FIG. 7 thereof;

FIG. 10 is a second embodiment of FIG. 1, it being understood that the undisclosed, right-side, left-side, bottom and top views the same as in FIGS. 2, 3 and 4;

FIG. 11 is an enlarged fragmentary cross-sectional view taken along lines 11—11 of FIG. 10; and,

FIG. 12 is a perspective view of the second embodiment thereof.

The broken lines showing the outlines of note paper on FIGS. 1, 2, 3, 4, 6, 9, 10 and 12 are for illustrative purposes only and form no part of the claimed design.
